UNITED STATES PATENT OFFICE.

JEROME JOHN SOUTH, OF MEMPHIS, TENNESSEE.

CONVERTIBLE CHAIR.

1,238,452.

Specification of Letters Patent. Patented Aug. 28, 1917.

Application filed May 10, 1916. Serial No. 96,617.

To all whom it may concern:

Be it known that I, JEROME J. SOUTH, a citizen of the United States, residing at Memphis, in the county of Shelby and State 5 of Tennessee, have invented a new and useful Convertible Chair, of which the following is a specification.

This invention has reference to convertible chairs, and its object is to provide a 10 chair which may be converted from a chair to a table, or vice versa, at will.

In accordance with the present invention the chair comprises a stool or body part and an extended plane portion serving either as 15 the back of the chair or the top of the table, and said back or table top is provided with supports constituting the arms of the chair when the device is used as a chair, while the stool part has members coacting with the 20 arms, and both the arms and said members, which latter are in the nature of posts, have interlocking devices whereby that portion of the chair constituting the back is movable to convert the device into a table and is 25 securely held in either position without the aid of locks or latches or similar devices which must be separately manipulated. The securing devices hold the table top in the table position or in the chair-back position 30 securely in a manner to be resistant against any ordinary forces liable to disturb the proper relation of the parts, but readily yieldable to purposely applied forces changing the chair to a table, or vice versa.

The invention will be best understood 35 from a consideration of the following detailed description, taken in connection with the accompanying drawings forming part of this specification, with the further understanding that while the drawings show a 40 practical form of the invention, the latter is not confined to any strict conformity with the showing of the drawings, but may be changed and modified so long as such 45 changes and modifications come within the scope of the appended claims.

In the drawings:—

Figure 1 is a perspective view of the chair structure with the parts related to constitute a chair.

Fig. 2 is a perspective view of the structure with the parts related to constitute a table and showing a drawer in the body or stool part of the chair drawn out.

Fig. 3 is a detail elevation with some parts in section, showing other parts in dotted lines, and indicating the position assumed by

the interlocking parts either in assembly or while being disengaged.

Fig. 3^a is a section on the line 3^a—3^a of Fig. 3.

Fig. 4 is a longitudinal vertical section through the connecting parts between the table top and body of the chair when in the table position.

Fig. 5 is a view similar to Fig. 3, but showing the parts assembled as a chair.

Fig. 6 is a view similar to Fig. 5 but showing the same parts when associated as a table.

Fig. 7 is a detail section to show a buffer structure preventing the chair back from engaging the chair legs.

Fig. 8 is an elevation of a portion of the chair structure showing a means for temporarily locking the parts against displacement.

Fig. 9 is a section on the line 9—9 of Fig. 8.

Referring to the drawings there is shown 80 a chair base or stool 1 with legs 2 and a seat portion 3 designed when the structure is used as a chair to receive a seat cushion 4. The legs are ordinarily provided with casters 5 and the base may have a box or body 85 portion 6 into and out of which there is arranged to slide a drawer 7 having a front 8, which, in the particular showing of the drawings, is so arranged as to constitute the front panel 8 of the body 6. This panel 8 90 is made to simulate other panels of the body portion 6 connecting the legs 2, so that when the drawer is pushed in the fact that the body of the chair is provided with a drawer is unnoticeable. This feature may be made 95 more or less secret by providing a hidden lock accessible from only the under part of the chair, so that only those knowing the secret of the chair will be able to open the drawer, while to others the presence of a 100 drawer could not be suspected.

Secured to each side panel of the body 6 about midway of the length thereof and rising above the top of the stool part of the chair are posts 9 each having an elongated 105 socket plate 10 set into its outer face and secured to the posts by screws 11 or in any other suitable manner. The socket plate 10 tapers from one end to the other, the wide end being the top in the installed position of the plate and being there freely open. The socket plate is in the main a flat plate with marginal flanges 12, 13 extending lengthwise of the sides of the plate. The flange 12

near the upper or wider end of the plate has a notch 14 cut out of it to a depth less than the depth of the flange, while the flange 13 stops short of the upper end of the socket 5 plate, the post being correspondingly cut away, as indicated at 15.

Adapted to the socket plate 10 is a taper plate 16 having a marginal flange 17 extending all about it except for a cut away 10 portion leaving an opening 18 therein at one side near the smaller end of the plate. Extending along the longitudinal center line of the plate throughout the greater portion of its length is a slot 19 opening through a side 15 extension 20 at the side of the plate where the flange 17 is omitted. At the small end the plate is rounded and is provided with a longitudinally extended lug or nose 21 for a purpose which will hereinafter appear. 20 The plate 16 is provided with holes 22 at suitable points along the marginal portion near the flange 17 for the passage of screws 23.

The plate 10 near the wide end midway 25 between the sides of the plate is formed with an outstanding lug 24 provided with a circumferential channel 25 next to the plate, wherefore the lug is in the form of a channeled or headed lug. The neck of the lug 30 is of such diameter as to be readily accommodated in the slot 19 and to pass into and out of the slot through the side extension 20, while the length of the neck of the lug corresponds to the thickness of the plate 16 35 where traversed by the slot 19, so that the headed lug 24 when in the slot 19 serves as a retaining or holding member for the plate 16, but permitting longitudinal and rocking movements of the plate 16, all for a purpose 40 to be described.

There is also provided a plane member 25^a of sufficient size to serve either as a chair back or as a table top. Ordinarily the plane member 25^a is somewhat longer than wide, 45 although any particular shape is not obligatory. It is, however, wider than the stool portion of the chair. Attached to the member 25^a are arms 26, each having curved side portions 27 and rounded at the ends remote 50 from the member 25^a, as indicated at 28. The particular curvature described is not obligatory but provides convenient arm supports when the device is being used as a chair. The plates 16 are made fast to what 55 may be termed the arms 26 by the screws 23, and the spread of the arms is such that when the parts are assembled the arms are exterior to the posts 9, although even in this respect such particular positioning of 60 the parts is not obligatory, especially as the plates 10 and 16 are rights and lefts made of cast or stamped metal, and, therefore, the arms may be placed either between or exterior to the posts 9. The plates or castings 65 16 are disposed lengthwise of the arms and

therefore perpendicular to the plane of the member 25^a.

Considering the device as a chair, the member 25^a constitutes the back of the chair and the members 26 the arms of the chair. 70 In assembling the back and arms the parts are first related as shown in Fig. 3, that is, the back and arms are tipped with the front ends of the arms lower than the rear ends thereof, and sufficiently to permit the necks 75 of the lugs 24 to enter the lateral openings 20 of the slots 19 with, however, the nose 21 of each plate 16 entering the respective socket plate 10 in such relation to the flange 12 thereof as to escape interference therewith. When, however, the main part of the slot 19 is reached the nose 21 is opposite the cut away portion or recess 14 of the flange 12, and may enter the latter. Since this cut away portion does not extend to the full 85 depth of the flange 12 the nose 21 is of less extent laterally of the plate 16 than is the flange 17. Immediately adjacent to the nose 21 the narrow end of the plate 16 is formed with a rounded shoulder 29 engaging that portion of the flange 12 between the recess 14 and the wide end of the plate 10. This prevents the plate 16 with the arm carrying it from moving lengthwise of the plate 16 when the arm is substantially horizontal, since the slot 90 19 then in line with the lug 24 would otherwise permit such movement. That end of the slot 19 toward the nose 21 has a slight terminal inset 30 forming a seat for the neck of the button 24 when it is in the longitudinal 100 center line of the plate 16, and then the nose 21 hooks under that end wall of the recess 14 toward the large end of the plate 10. Under these circumstances the arms 26 drop at the ends toward the member 25^a until the 105 then lower edges of the plates 16, which plates are about or a little lower than the horizontal enter the recesses 15 in the posts 9 and bear upon the upper ends of the flanges 13. The member 25^a, which under these circumstances constitutes the back of the chair, drops behind the stool part or body portion of the chair until the then lower edge of the back 25^a engages the rear legs of the chair near their lower ends. Marring of the finish 115 of the legs of the chair is prevented by rubber or other suitable buffers 31 carried at appropriate points by the under or inner surface of the back 25^a.

By means of snap buttons 32 in part carried by the chair back 25^a and in part carried by a cushion 33, such a cushion is made fast to the inner face of the back 25^a in co-active relation to the seat cushion 4, while both cushions may be readily removed when 125 not needed. The snap buttons 32 are usually of the ordinary type of snap button.

While the weight of the chair back 25^a is usually sufficient to hold it in place, it is quite possible that a heavy person seated in 130

the chair will on attempting to rise therefrom press with considerable weight on the then outer or front ends of the arms 26, and such pressure might at times be sufficient to 5 raise the back of the chair. This is avoided by providing a spring catch 33^a on the back 25^a and a keeper 34 at an appropriate point on one of the legs 2, so that the catch 33^a will snap into the keeper 34 when the back 10 25^a is in the lowered position like that shown in Fig. 1.

By releasing the chair back 25^a from the keeper 34, the chair back may be readily lifted, turning about the lugs 24 as pivots 15 until the plates or castings 16 are in upright positions, whereupon the back 25^a then serving as a table top is lowered with the plates or castings 16 entering the socket plates 10 until they are firmly lodged therein, being centered and held by the inner taper walls of the flanges 12 and 13, and the outer taper walls of the flange 17, the 20 plate 16 readily moving to such position because of the presence of the slot 19, the walls 25 of which surround the neck of the lug 24. Now the posts 9 and arms 26 with the coacting plates 10 and 16 rigidly support the table in the level or table position against any possibility of displacement other than 30 designed displacement by lifting the table member 25^a until the lug 24 is once more at the end 30 of the slot 19, whereupon the table top 25^a may be lowered to the position shown in Fig. 1 when such table top 35 becomes a chair back.

In both conditions, that is, with the device arranged for use as a chair or arranged for use as a table the parts are effectively connected against accidental displacement 40 and are resistant to all ordinary forces, except those purposely applied to change the device from one kind of use to the other. When used as a chair the chair back readily gravitates to its proper position to there 45 automatically lock, because of the catch 33^a and keeper 34, but even in the absence of such catch it is proof against displacement except to certain extraordinary forces seldom applied for the action of gravity 50 greatly preponderates, and it is only when extra heavy forces are applied at the outer extremities of the arms 26 that the back is at all liable to displacement.

When the member 25^a is moved to the 55 table position the connections are particularly rigid because of the action of gravity and the taper form of the connecting parts necessitating the lifting of the member 25^a then constituting the table top to a considerable height before it can be moved to the 60 chair back position. Under such conditions the table top is not only very rigidly connected to the stool part of the chair, but maintains its position by gravity against 65 disturbing forces.

Should it be desired to disconnect the member 25^a with the arms 26 from the stool portion of the chair, this is readily accomplished by a reversal of the action of assemblage indicated in Fig. 3.

70

In neither instance is it necessary to employ any tools, or to disconnect the fastening devices except the simple movement of the catch 33^a to the unlatched position when the catch 33^a is present.

75

Certain of the following claims are drawn in sufficiently comprehensive language to cover such subject matter of my application, No. 111,221, filed July 25, 1916, for a convertible chair as is common to both applications. For instance, the chairs in both cases have a basic portion with uprights and preferably single posts on opposite sides rising above the basic portion and located about midway between the front and back of the 85 basic portion. The chair back, which is convertible into a table top, has arms on opposite sides fixed to the back and projecting therefrom in substantially perpendicular relation thereto and so spread apart as to embrace the posts, so that the arms are exterior to the posts. Furthermore, in both cases the arms and posts are elongated and are arranged to interlock, when associated lengthwise, to hold the chair back firmly in 90 the table position, with the posts and arms constituting the sole support for the table top in the table position and practically the sole support for the chair back when in the 95 latter position.

100

What is claimed is:—

1. A convertible chair and table structure, comprising a basic portion or support with posts rising therefrom on opposite sides, a back member for the chair having arms on 105 opposite sides constituting arm rests for the user of the chair, and coacting taper members on the posts and arms movable one into and out of the other for holding the back member in either the chair or table position. 110

2. A convertible chair and table structure, comprising a basic portion or support with members uprising from opposite sides thereof, a back member for the chair, and arms constituting the arm rests of the chair, 115 said arms being fixed to and projecting from the back member, and coacting automatically interlocking devices on the upstanding members and the arms, respectively, and having means for supporting the arms and back member and locking the latter in the table position and also having means for supporting and holding the arms and back member in the chair-back position.

120

3. A convertible chair and table structure, comprising a basic portion or support with posts rising therefrom on opposite sides, a back member for the chair comprising a table with arms on opposite sides constituting arm rests for the user of the chair, and 125 130

coacting taper members on the posts and arms pivotally connected together and one movable into and out of telescoping relation to the other and when in the telescoping relation holding the chair back member in the table position.

4. A convertible chair and table structure, comprising a basic portion or support with posts rising therefrom on opposite sides, up-

10 right taper socket plates in each post with the wide end uppermost, a back member comprising a table having arms on opposite sides constituting the arm rests for the user of the chair, and other socket plates secured

15 to the arms and telescoping into and movable out of the socket plates to support the back member either in the chair-back position or in the table position.

5. A convertible chair and table structure,

20 comprising a basic portion or support with posts rising therefrom on opposite sides, a back member having a plane portion and arms on opposite sides thereof extending perpendicularly to the plane portion and 25 constituting arm rests for the user of the chair, and connections between the arms and posts each comprising a taper socket plate on a respective post with said socket plate having the wide end uppermost and adja-

30 cent thereto provided with an outstanding headed lug, and said plate having side flanges with one recessed near the wide end of the plate and the other cut away near the wide end of the plate, and another plate

35 fast to a respective arm, said second plate having a longitudinal slot with a side opening adapted to receive the headed lug, and at the small end provided with a nose adapted to enter the recess in one of the side

40 flanges of the socket plate.

6. A connecting means for the body and back portions of a convertible chair and table structure, comprising two plates each longitudinally tapered with one adapted to

45 telescope in the other, one of the plates having side flanges with one flange recessed near the large end of the plate and the other flange cut away near the same end of the plate, and said plate near the large end

50 having an intermediately located headed lug projecting from the plate, and the other plate having a longitudinal central slot with a laterally offstanding outlet near the small end of the plate to receive the headed lug, and said second plate having at its small end

55 a longitudinally projecting nose and adjacent to the nose provided with a rounded shoulder, said nose being adapted to enter the recess on the corresponding side flange

60 of the plate and the second plate being adapted to the cut away portion of the sec-

ond-named flange of the first-named plate.

7. A convertible chair and table structure, comprising a basic portion provided with upstanding posts on opposite sides, a back 65 member comprising a plane portion and arms projecting from one face thereof near opposite sides and spaced to be lodged exterior to the posts, and coacting pairs of connecting members between the posts and 70 arms, each pair of members having one of its elements carried by the respective post on the outer face thereof and the other element being carried by the respective arm on the inner face thereof, said elements of each 75 pair being slidable one on the other and also pivoted one to the other and movable into automatic locking relation when the back member is moved into position to constitute a chair back and when it is positioned to 80 constitute a table.

8. A convertible chair and table structure, comprising a basic portion, single posts up- 85 standing at each side of and substantially midway between the front and back of the basic portion, a back member having fixed arms at each side projecting therefrom sub-stantially midway between the ends of the back member, and means for pivotally connect- 90 ing the posts and arms together so as to permit of a movement of the back mem-ber from the chair back position to the table position, the arms of the chair back embrac-ing the posts rising from the base, and said arms and posts constituting the sole sup- 95 porting means for the back in the table position.

9. A convertible chair and table structure, comprising a basic portion having single up- 100 standing posts at the opposite sides, a back member having fixed arms at each side, and means for pivotally connecting the arms and posts together so as to permit of a movement of the back from a chair back position to the table position, the arms interlocking with 105 the posts and constituting the sole supporting means for the back in the table position.

10. A convertible chair and table struc- 110 ture, comprising a basic portion and a back member, the basic portion having upstand- 115 ing elongated posts on opposite sides and the back member having elongated projecting arms fixed thereto on opposite sides and interlocking in one position with the posts, and said arms and posts constituting the sole supporting means for the back member in the table position.

In testimony that I claim the foregoing as my own, I have hereto affixed my signature in the presence of two witnesses.

JEROME JOHN SOUTH.
